ATTORNEY

UNITED STATES PATENT OFFICE.

GEORGE E. GIBBS, OF ATTLEBORO, MASSACHUSETTS, ASSIGNOR TO AMERICAN RE-ENFORCED PAPER COMPANY, OF ATTLEBORO, MASSACHUSETTS, A CORPORATION OF MASSACHUSETTS.

ROVING-FEEDING MECHANISM.

Application filed November 8, 1928. Serial No. 318,032.

This invention relates to improved mechanism for advancing rovings from bales or other sources of supply into parallel relation to form a sheet of rovings.

5 It is found that unspun fibres of long staple form excellent paper reenforcing strands, and mechanism has been proposed heretofore for adhesively securing a thin layer of long unspun fibres to a sheet of paper to reenforce 10 the paper. In some cases the reenforcing fibres are applied longitudinally of the sheet or sheets of paper to be reenforced as disclosed in the Howard and Sharp United States Patent No. 1,565,009, dated December 15 8, 1925, while in other constructions the reenforcing fibres are applied both longitudinally and transversely of the sheet or sheets of paper to be reenforced as disclosed in the Howard United States Patent Numbered 20 1,590,167, dated June 22, 1926.

In each of the patents just mentioned the reenforcing fibres are supplied to the paper reenforcing machines in the form of rovings that are laid side by side to form a sheet of 25 fibres, which after being combed and drawn out is applied to the adhesive covered sheet of paper to be reenforced.

The rovings are supplied in the form of bales to the paper reenforcing manufacturers 30 and since a large number of rovings may be employed to reenforce a wide sheet of paper and each roving bale is relatively large, the entire group of bales from which the rovings are drawn to the paper reenforcing machine 35 occupy considerable floor space. Much difficulty has therefore been experienced heretofore in devising a satisfactory construction whereby the rovings from the various bales or other sources of supply may be led in the 40 form of a sheet to the paper reenforcing machine.

The present invention therefore relates to improved mechanism for guiding a large number of rovings from bales or other 45 sources of supply into position to form a traveling sheet of rovings. One of the features of the present invention resides in spaced bars or rollers that are disposed above the sources of roving supplies to support 50 the advancing rovings that are drawn from

the sources of supply, and another feature resides in guides associated with these bars and adapted to guide the rovings side by side into the sheet forming relation.

While the roving feeding mechanism of 55 the present invention is designed more particularly for use in supplying a sheet of rovings to a paper reenforcing machine it obviously may be employed in various fields where a relatively wide sheet of rovings is 60 desired.

The various features of the invention and novel combination of parts will be best understood from the following description 65 when read in connection with the accompanying drawings.

In the drawings:—

Fig. 1 is a perspective view of a machine constructed in accordance with the present invention;

Fig. 2 is a longitudinal sectional view through the machine of Fig. 1, and

Fig. 3 is a perspective view of a roving guide and its supporting bar.

In the embodiment of the invention illustrated in the drawings the roving supporting bars or rollers 10 are mounted upon the horizontally extending side rails 11 which rails are supported a substantial distance above the floor of the building by the uprights as 80 shown.

The roving supporting bars or rollers 10 are preferably supported in staggered relation by the side rails 11 as shown, and the rovings 12 preferably pass alternately over 85 and under the bars 10. This is desirable to maintain pressure upon the opposite faces of the sheet of rovings to hold the individual fibres in contact with each other to thereby prevent the rovings from elongating unduly 90 under the advancing pull to which they are subjected.

The bars or rollers 10 may be journaled in the supporting brackets 13 for rotative movement, or if desired they may be non- 95 rotatively supported. A greater pull necessarily will be required to advance the rovings over fixed bars than over rotating bars or rollers, but any tendency of the loose fibres to wrap around the rotating bars may 100

be prevented by mounting these bars so that they will not rotate.

The rovings 15 are usually supplied to the user in the form of bales 16, and in accordance with the present invention these bales or other sources of roving supply may be placed upon the floor of the building in rows beneath the bars 10, as will be apparent from Fig. 1. The individual rovings 15 are led upwardly from the bales or the like 16 over the guide bars 10 and then forward over the series of guide bars in the direction indicated by the arrow.

Since the bales 16 are of substantial size and occupy considerable floor space, the number of bales that can be arranged side by side transversely of the machine is necessarily limited, and in order to obtain sufficient floor space for the large number of bales required to supply the desired number of rovings, these bales are preferably arranged in successive rows beneath the guide bars 10 throughout the length of the machine, as will be apparent from the drawing.

The rovings supplied by a transversely extending row of bales 16 are led upwardly about a bar 10 disposed over such row of bales, and are then led forward over the series of bars lengthwise of the machine as indicated by the arrow to form the sheet of rovings 17 shown at the front of the machine as extending downwardly through an opening 18 in the floor of the building.

It is necessary to guide the rovings as they pass upwardly around the guide bars 10 to direct them over the bars and lengthwise of the machine so that the rovings will form the desired sheet 17, and this is accomplished in the construction shown by providing adjacent each bar or roller 10 the required number of roving guides 19 that are constructed to be adjustably mounted upon the supporting bars or angle irons 20 that are secured to the rails 11. The arrangement is such that each guide 19 may be adjusted lengthwise of its supporting bar 20. This adjustable feature is obtained in the construction shown by providing each roving guide 19 with a laterally extending portion 21 having a downwardly extending lip 22 adapted to receive a set screw 23 positioned to engage the angle iron and clamp the guide in the desired position of adjustment. The construction of each roving guide 19 is preferably such that a roving may be moved laterally into and out of engagement with the guide, as will be apparent from Fig. 3, wherein it will be seen that the guide is provided with the spaced guiding wings 24.

It will be apparent from the foregoing that several rovings 15 are led upwardly from their sources of supply over a guide bar or roller 10 and then lengthwise of the roving feeding machine over and under the

alternate bars 10 as shown, and that each guide 19 may be adjusted lengthwise of its supporting bar to guide its particular roving lengthwise of the machine to form the desired roving sheet 17.

The series of bars 10 are preferably supported a substantial distance from the floor of the building, as will be apparent from the drawing, in order to allow sufficient clearance space between the roving bales and guides 19 to permit the kinks or twists in the rovings that are drawn upwardly from the bales to straighten out before these kinks or twists reach the guides.

The roving feeding machine forming the subject matter of the present invention necessarily occupies considerable floor space and it will therefore be found desirable in many cases to mount this machine upon the floor of a building which is disposed above the paper reenforcing machine or other machine to which the sheet 17 of rovings may be fed, as this will secure a substantial saving in floor space adjacent the machine to which the sheet of rovings may be fed. Such arrangement is readily accomplished by drawing the sheet 17 of rovings downwardly through an opening 18 in the floor. The sheet advancing means employed in the present construction consists of a pair of rollers 25 and 26 which may be disposed below the floor in which the opening 18 is formed to receive the sheet of rovings therebetween, and one of these rollers may be driven by any suitable means such as a worm gear 27 which meshes with and is driven by a worm 28 mounted upon the driving shaft 29.

The reenforcing fibres usually employed heretofore in reenforcing paper have been of long staple such as secured from flax, sisal, hemp or the like, and it is found that if the bars or rollers 10 engage the opposite faces of the sheet of rovings as shown, the untwisted rovings formed of these long unspun fibres may be pulled from the source of supply 16 through the guides 19 and over the various guide bars 10 without unduly attenuating the rovings, by merely driving the cooperating rollers 25, 26.

It will be seen from the foregoing that the roving feeding machine forming the subject matter of the present invention is simple in construction and that since the roving guides 19 are adjustable lengthwise of their supporting bars, these guides are readily adjusted to direct the rovings lengthwise of the supporting structure as desired. Furthermore, since the guides 19 are only partially closed, the rovings may be readily moved laterally into and out of engagement with a guide, thus simplifying the operation of placing the rovings in the guides.

What is claimed is:—

1. A machine for assembling rovings of fibres side by side to form a fibrous sheet,

comprising a series of spaced bars mounted transversely of the machine in elevated relation to the floor and above separate bales or other sources of roving supply to support the advancing rovings, guides for the individual rovings mounted adjacent the bars for adjustment lengthwise of the bars to direct the rovings lengthwise of the machine over the spaced bars to form the desired sheet, and power driven means positioned to engage the sheet of rovings to pull the individual rovings from the source of supply over said bars.

2. A machine for assembling rovings of fibres side by side to form a fibrous sheet, comprising a series of spaced rollers mounted in elevated relation to the floor above separate bales or other sources of roving supply to support the advancing rovings, guides for the individual rovings mounted adjacent the rollers for adjustment transversely of the machine to direct the rovings longitudinally of the machine over the rollers, and driven means positioned to engage the sheet of rovings and pull the individual rovings from the source of supply over the rollers.

3. A machine for assembling rovings of fibres side by side to form a sheet, comprising a supporting frame, a series of bars mounted upon the frame in spaced relation to each other and at a substantial distance from the floor to support rovings drawn upward from the floor and over the bars, guides adjustably mounted adjacent the bars for adjustment transversely of the machine to direct the rovings drawn over the bars into parallel relation to form the roving sheet, and power actuated means positioned to engage the sheet of rovings to pull the individual rovings from the source of supply over said bars.

4. A machine for assembling rovings of fibres side by side to form a sheet, comprising a supporting frame, a series of bars mounted upon the frame in spaced relation to each other and at a substantial distance from the floor to support rovings drawn upward from the floor and over the bars, power actuated means adapted to engage and advance the sheet of rovings and thereby pull the individual rovings from their source of supply over said bars, and guides mounted adjacent the bars to direct the rovings drawn upwardly from the source of supply over the bars to the sheet forming position and each guide being constructed so that a roving may be moved laterally into and out of engagement with the guide.

5. A machine for assembling rovings of long unspun fibres side by side to form a sheet, comprising a supporting frame, a series of bars mounted upon the frame in spaced relation to each other and at a substantial distance from the floor to support rovings drawn upward from the floor over

the bars, power actuated means for pulling the rovings from the source of supply over the bars lengthwise of the machine, guides mounted adjacent the bars and adjustable lengthwise thereof to direct the rovings drawn upwardly from the source of supply to the sheet forming position, and each guide having an entrance opening through which the rovings can be moved laterally into the guide.

In testimony whereof, I have signed my name to this specification.

GEORGE E. GIBBS.
